DESIGN.

—o—
I. GOODMAN.
TRIMMING.

No.19,610.

Patented Jan. 28, 1890.

UNITED STATES PATENT OFFICE.

ISAAC GOODMAN, OF PHILADELPHIA, PENNSYLVANIA, ASSIGNOR TO HIM-
SELF, ABRAHAM KAUFMAN, WILLIAM KAUFMAN, AND SYLVESTER C.
KLOPFER, ALL OF SAME PLACE.

DESIGN FOR TRIMMING.

SPECIFICATION forming part of Design No. 19,610, dated January 28, 1890.

Application filed December 23, 1889. Serial No. 334,791. Term of patent 3½ years.

To all whom it may concern:

Be it known that I, ISAAC GOODMAN, a citizen of the United States, and a resident of Philadelphia, Pennsylvania, have invented a
5 Design for Trimming, of which the following is a specification.

My design is fully shown in the accompanying photographic illustration.

The design comprises a series of elongated
10 figures formed by a double cord and arranged side by side, the lower end of each of these figures being pointed and its upper end contracted, and between these contracted upper ends of the figures are loops or festoons. Each
15 of the elongated figures also contains one or more ornaments of an inverted-V shape, the

number of these ornaments depending upon the depth of the trimming, as will be understood on reference to the three pieces of trimming shown in the illustration.

I claim—

The design for trimming, substantially as described, and as shown in the accompanying drawing.

In testimony whereof I have signed my name 25 to this specification in the presence of two subscribing witnesses.

ISAAC GOODMAN.

Witnesses:

R. SCHLEICHER,
HARRY SMITH.
